UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed December 12, 1919. Serial No. 344,303.

To all whom it may concern:

Be it known that I, REUBEN B. BENJAMIN, a citizen of the United States, residing at Chicago, in the county of Cook and State 5 of Illinois, have invented new and useful Improvements in Electrical Connector Devices, of which the following is a full, clear, concise, and exact description, reference being had to the accompanying drawing, 10 forming a part of this specification.

This invention relates to electrical connector devices.

One of the purposes of this invention is to provide a suitable connector device for use 15 for low voltage circuits. In farm lighting systems where low voltage circuits are generally used, the same lighting power is desired as in the higher voltage circuits.

It is necessary, therefore, in farm lighting 20 systems, using low voltage, that the translating device used (such as lamps, heaters and so forth) be of low resistance so that a high amperage is necessary. Therefore, where plug-in devices are to be inserted into 25 receptacles, this high amperage at the point of connection would burn out the contacts unless a quick and positive connection is made between the plug and receptacle.

It is, therefore, one object of my invention 30 to provide a connector device whereby a positive and quick electrical connection is accomplished between the parts.

Another object of my invention is to provide means whereby upon the initial engagement 35 of the parts with respect to each other, no electrical connection is accomplished but a substantial resistance is met with and whereby upon further insertion of the member, the resistance is overcome and a positive 40 and quick electrical connection is effected.

Another object is in the provision of these means in a neat and compact arrangement.

Further objects will appear from the description and appended claims.

45 In the drawings—

Fig. 1 is a longitudinal side elevation of the connector device;

Fig. 2 is a longitudinal sectional view on the line 2—2 of Fig. 1 showing the parts out 50 of engagement;

Fig. 3 is a view on the line 3—3 of Fig. 2;

Fig. 4 is a view on the line 4—4 of Fig. 2 looking in the direction of the arrows;

Fig. 5 is a view on the line 5—5 of Fig. 2 55 looking in the direction of the arrows;

Fig. 6 is a detail sectional view showing the cap blade entering the receptacle; and Fig. 7 is a sectional view on the line 7—7 of Fig. 6.

In order to give a general idea of the 60 invention, it is here stated that the construction shown comprises a receptacle 10 having a pair of wiring terminals 11 for the feed wires and a pair of spring contact devices 12 and 12^a electrically connected with the wiring terminals respectively for engagement with the contact blades 13 on the cap 14.

In order that the first engagement between the two parts of the connector device may 70 not establish an electrical connection, the tips of the spring contact device 12 of the receptacle are provided with insulating blocks located in the path of the contact blades of the cap so that the contact blades, 75 when the connection is being made, first engage the insulating blocks and cause a resistance to the making of the connection which the person who is making the connection overcomes by an energetic push on the cap causing the actual electrical connection to 80 be quickly made.

The receptacle comprises a base portion 15 to which the wiring terminals 11 and spring contacts 12 and 12^a are secured and a cover portion 16 having recesses 17 into which the spring contacts extend and having restricted openings 18 leading to the recesses, the restricted openings affording a guide and passage for the contact blades of the cap.

The cap portion 14 comprises in addition 90 to the contact blades 13 previously referred to an insulating base 14^a on which the contact blades are supported, and a pair of binding screws 19, one for each of the contact blades, 95 for securing the wires and electrically connecting them with the contact blades.

To give a more detailed description of my construction, the receptacle 10 comprises the insulating base 15 having the recesses 17 therein, in which recesses are mounted binding plates 20 having binding screws tiltably mounted therein. The construction of the binding plate and tilttable screw shown herein have been claimed in my application S. N. 343,250 filed December 8th, 1919. 105

To state briefly, this construction comprises a binding plate 20 having a fulcrum portion 21 thereon which is secured by screws 22 to the insulating base 15. The binding plate is apertured at 23 and has a binding 110

screw passing therethrough, said screw having a nut 25 thereon.

As shown in Fig. 6, the nut 25 bears on the fulcrum portion 21 of the binding plate 5 so that the binding screw may tilt in the aperture 23 and with respect to the binding plate to hold wires of unequal diameters between the head of the binding screw 24 and the binding plate 20.

10 The upwardly extending spring contact fingers are secured to the binding plate 20 (Fig. 7), by means of two integrally formed portions 26 upon which the spring contact fingers are riveted to hold the spring contact fingers securely in place in an upright position.

As shown in Fig. 5, the upwardly extending spring contact finger 12 has a piece of insulation 27 thereon (which may be of a 20 stamping of sheet fibre) this contact finger being slotted and the piece of insulation inserted in said slot after which insertion the contact finger is crimped at 28 to cause the edges of the slot to engage depressions in the piece of insulation whereby it is securely held in the contact finger 12.

Secured to the base 15 by means of screws 29, is the cover portion 16, which is recessed to receive the contact fingers which extend 30 upwardly from said base member. The contact fingers 12 which support the pieces of insulation extend into said recesses and are in direct alignment with the guiding slots 18 in the oval portion of the cover 16. 35 The spring contact fingers 12^a, however, extend into offset recess portions 30 and have a limited movement within said recesses, as shown in Fig. 2, the object of these offset recesses being to keep the contact fingers 12^a out of the path of the blades 13 when entering the guide slots in the cover portion to avoid premature electrical connection of said contact blades 13 with said fingers 12^a.

40 The cap 14 comprises an insulating base 14^a which has secured thereto the contact blades 13 which blades are secured in place by means of metal bushings 31 which are moulded into the insulating base, these bushings having portions 32 extending through 45 openings in the base portions 33 of the blades 13 and being riveted over to hold the blades in place. These bushings serve another function in that they are internally screw threaded to receive the binding screws 19, 50 the insulating base having a central opening for the passage of the wires which are connected to the binding screws.

55 In use, when the blades 13 are inserted into

the guiding slots 18 in the cover portion 16, they first engage the pieces of insulation 27, 60 as shown in Fig. 6, this engagement forming no electrical connection between the parts but instead offering a substantial yielding resistance, the natural effect of which is to cause the user to exert a more energetic push 65 on the cap, causing the contact blades 13 to get past the slanting portion of the insulated pieces, where the resistance becomes much less whereby said blades and spring contact fingers will engage each other quickly 70 and effect a quick and positive electrical connection of the parts.

While I have herein shown but one form of my invention, many changes and modifications thereof may be made without departing from the spirit and scope of my invention. 75

Having thus described my invention, what I claim as new and desire to secure by Letters Patent is:

1. A receptacle for cooperation with a plug-in member, said plug-in member comprising an insulating base, and a pair of contact blades supported thereby, said receptacle comprising an insulating base and 80 a pair of contact fingers supported thereby for engagement with the blades of the plug-in member respectively, said insulating base of said receptacle being recessed to receive said contact fingers and having openings 85 through which the blades of the plug-in member can be inserted for engagement with the contact fingers, and means whereby on inserting the plug-in member, a yielding resistance is met before the electrical connection is made between the blades and contact fingers, said means comprising a piece of insulation carried by the tip of one of said contact fingers.

2. An electrical connector device comprising 100 an insulating base, a contact finger supported thereby and having a slot therein, and an insulating member secured in said slot for engagement with a contact of a cooperating connector device.

3. An electrical connector device comprising 105 an insulating base, a contact supported thereby having a slot therein, an insulating member supported by said contact having notches for engagement with the edges of 110 said slot, that portion of the contact finger which comprises the slot being crimped to hold the edges of said slot in said notches.

In witness whereof, I have hereunto subscribed my name.

REUBEN B. BENJAMIN.
